UNITED STATES PATENT OFFICE.

WALTER D. MACLEITH, OF ST. PAUL, MINNESOTA, ASSIGNOR OF ONE-THIRD TO UNION FIBRE COMPANY, OF WINONA, MINNESOTA, A CORPORATION OF MINNESOTA.

INSULATING FLOOR CONSTRUCTION.

1,226,788.

Specification of Letters Patent. Patented May 22, 1917.

Application filed December 7, 1914. Serial No. 875,874.

To all whom it may concern:

Be it known that I, WALTER D. MACLEITH, a citizen of the United States, residing at St. Paul, in the county of Ramsey and State 5 of Minnesota, have invented certain new and useful Improvements in Insulating Floor Construction, of which the following is a specification.

My invention relates to improvements in 10 insulating floor construction, its object being particularly to provide an improved insulated construction of flooring and connected side wall designed for deadening the flooring and elastically taking up in the 15 most efficient manner the jars caused by articles falling upon the floor, a further object being to provide a construction which will prevent the water going into the interior insulation and deteriorating the same. 20 To this end the invention consists in the construction, combination, and arrangement of parts hereinafter described and claimed.

In the accompanying drawings forming part of this specification,

25 Figure 1 is a side view of one corner of a floor and connected wall broken away embodying my improved features of invention; and

Fig. 2 is a vertical section on line $x-x$ 30 of Fig. 1.

Referring to the drawings A represents a side wall of the room, and B spaced floor joists. In building up the floor construction strips 2 will first be secured along the 35 inner faces of the floor joists and upon these are positioned strips of insulation 3 supporting the flooring 4. The flooring 4, as shown best in Fig. 2, projects above the upper faces of the floor joists. Upon the flooring 4 is placed a sheet of resilient insulating material 5, the raised position of the flooring with respect to the joists leaving an air space, as shown in Fig. 2, between the joists and insulating material. Loosely 40 laid upon the top of the insulation 5 is the expanded metal 6. I then pour upon the expanded metal 6 a composition layer 7 in a soft condition and of such a character that contained heavy matter will sink and 45 form a solid mass embedding the expanded metal while the top of the layer will be lighter and resilient. I preferably use in forming this layer a composition of cork, sawdust, sand, cement, and alum mixed in 50 water. As shown I trowel the mixture up

along the side wall, covering the layer of material with suitable covering 8 as of linoleum.

The operation of the resilient insulation 3 and 5 with the air space above the joists 60 and the particular character of composition 7 result in making the floor soundproof to the maximum degree. I have found when heavy weights are dropped upon the floor the resilient top of the composition layer 7 65 becomes slightly indented, and the strains are thrown out mostly in a lateral direction above the hard, more solid bottom of the composition layer. The expanded metal anchors and makes more solid and firm the 70 lower hard portion of the composition layer. I have found a very small amount of the shock or noise passing through the composition layer, and what little does, is taken up by the insulating materials and the air 75 spaces. I thus secure a flooring that is essentially soundproof and highly efficient for hospital and similar purposes.

I claim as my invention:

1. A floor construction of the class described comprising floor supporting joists, 80 flooring arranged between said joists with its upper face standing above the upper faces of the joists, a resilient insulating sheet positioned upon said flooring leaving 85 an air space above the joists, and a composition layer upon said insulating sheet, said composition layer being relatively hard adjacent to the insulating sheet and relatively 90 resilient at the top.

2. A floor construction of the class described comprising floor supporting joists, 95 flooring arranged between said joists with its upper face standing above the upper faces of the joists, a resilient insulating sheet positioned upon said flooring leaving an air space above the joists, a composition layer upon said insulating sheet, said composition layer being relatively hard adjacent to the insulating sheet and relatively 100 resilient at the top, and anchoring expanded metal embedded in the lower half of said composition.

3. A floor construction of the class described comprising floor supporting joists, 105 flooring arranged between said joists, with its upper face standing above the upper faces of said joists, a resilient insulating sheet positioned upon said flooring leaving a space above said joists, and a composition 110

layer upon said insulating sheet, said composition layer containing relatively heavy materials which will settle to the lower portion of said composition and make the same firm and hard and containing materials which will leave the upper portion of said composition material relatively yielding.

4. A floor construction of the class described comprising floor supporting joists, 10 flooring arranged between said joists, with its upper face standing above the upper faces of said joists, a resilient insulating sheet positioned upon said flooring leaving a space above said joists, a composition layer 15 upon said insulating sheet, said composition

layer containing relatively heavy materials which will settle to the lower portion of said composition and make the same firm and hard and containing materials which will leave the upper portion of said composition 20 material relatively yielding, and openwork metal embedded in the lower relatively harder portion of said composition material for the purpose set forth.

In testimony whereof I affix my signature in presence of two witnesses.

WALTER D. MACLEITH.
